Specification for Design.

Patented May 16, 1911.

Application filed March 8, 1911. Serial No. 613,180. Term of patent 14 years.

To all whom it may concern:

Be it known that I, CHARLES K. SALISBURY, a citizen of the United States, residing at Milwaukee, in the county of Milwaukee and State of Wisconsin, have invented a new, original, and ornamental Design for Centrifugal-Separator Casings, of which the following is a specification, reference being had to the accompanying drawing, forming a part thereof.

Figure 1 is a perspective view looking at

the frame from one direction and showing my new design; and, Fig. 2 is a similar view looking at the other side thereof.

I claim:

The ornamental design for a centrifugal separator casing, as shown.

CHARLES K. SALISBURY.
